FOUNTAIN PAINT BRUSH

Hollis F. Mitchell, Indianapolis, Ind., assignor of twelve percent to William M. Clark, twenty-eight percent to William Emrich, Jr., and eight percent jointly to William M. Clark and William Emrich, Jr., both of Indianapolis, Ind.

Application March 20, 1937, Serial No. 132,004

10 Claims. (Cl. 15—128)

This invention relates to what is generally known as a fountain paint brush. This application is a continuation-in-part of a prior application, Serial No. 70,092, filed March 21, 1936, 5 entitled "Fountain paint brush device."

The chief object of this invention is to provide a fountain brush or like device construction which will eliminate the dipping of the brush into the material to be applied by the brush.

10 Another object of the invention is to provide for the flowing of the paint or like from the brush in band or stream form.

Another object of the invention is to arrange the brush such that as the bristles wear the immediate supply means for supplying paint to the bristles may be adjusted in accordance with bristle wear.

20 Another object of the invention is to flexibly connect the immediate paint supply means of the brush when desired, so that for certain classes of work (other than flat work) flipping of the paint due to bristle exposure of the supply means, is prevented.

25 The chief feature of the invention consists in the construction of a fountain brush capable of accomplishing the foregoing objects as well as all the objects recited by the aforementioned co-pending application and the features specifically disclosed herein are in addition to the features disclosed in the before mentioned co-pending application.

Still a further feature of the invention consists in providing a remote control device for the brush and mountable upon the brush to permit 35 the brush operator to hold the brush in any one of several different manners and yet at the same time have complete control over the paint supply.

Another feature of the invention consists in the addition of flared flexible tips upon the ends 40 of the bristle enclosed flexible paint supplying tubes, which flexible tips are also bristle enclosed.

Another feature of the invention consists in the detachable association of the several parts so 45 that not only can cleaning of the entire brush be effected most expeditiously and efficiently but the respective detachable parts are of such character that for replacement purposes, when the brush bristles are worn out, there is required only a new base with the new bristles supported thereby and new tube tips, if necessary.

Other features of this invention will be more fully set forth hereinafter in the detailed description.

55 The full nature of the invention will be under-

stood from the accompanying drawing and the following description and claims:

In the drawing, Fig. 1 is an enlarged central sectional view of a fountain brush embodying the invention, the valve control portion being shown 5 in elevation, the dotted lines indicating the final adjustment possible when the brush is practically worn out.

Fig. 2 is a sectional view of the brush shown in Fig. 1 but is taken at right angles thereto and 10 on line 2—2 of Fig. 1 and in the direction of the arrows, said brush, however, being shown provided with a remote control attachment.

Fig. 3 is a view similar to Fig. 2 and of a modified form of brush, the remote control attachment being omitted for clearness.

In Figs. 1 and 2 of the drawing, 10 indicates a base provided with a plurality of apertures 11 extending therethrough, the apertures being herein shown in alignment and parallel to each other. A central aperture 13 is also provided. The bristles 14 are suitably secured to the base. This may be of molded rubber, or the like, if desired. The aperture 13 may be threaded to receive the externally threaded tubular member 15 25 having the coaxial opening 16 therein.

Press-fitted or molded in the base 10 and positioned in the apertures 11, are the tubes 17 internally threaded as at 18 and terminating in a frusto-conical mouth 19.

A head structure 20 includes a chamber 21 and a flange 22, the latter bearing on the gasket 23 of suitable material and interposed between the flange and the base. The head 20 is nested in a well formed by the band 24 suitably secured to 35 and peripherally enveloping the base 10 and projecting in opposite directions therefrom to enclose the bristles adjacent their connection to the base and to form said well. The head 20 is apertured as at 25 adapted to receive a tubular portion 26, 40 the bore of the latter being internally threaded as at 27 and near its lower end being provided with transverse ports or passages 28 discharging to the chamber 21.

The tubular portion 26 suitably supports a 45 thumb operable valve 29 and connects as at 30 to a tubular handle structure broadly designated by the numeral 31, the latter terminating in a threaded tubular end 32 which mounts a retaining threaded collar or nut 33. The paint supply 50 is connected to end 32.

A remote control arrangement may be associated with said valve and the same is illustrated in Fig. 2. It includes an apertured anchoring end 34, a hand engageable portion 35, 55

the latter portion being channel or U-shaped in cross section and the sides 36 partially embracing the handle 31. Portions 35 and 36 are offset laterally and outwardly as at 37 and 38, 5 respectively, and thence downwardly as at 39 and 40, and the latter portion merges with the extension 41 of the portion 39. Suitably secured to the interior of portion 37 is a clip 42 and the same is adapted to lie below the head of the 10 valve 29 while the portion 39 lies above the same. The side portions 40 adjacent thereto thus form with portions 39 and clip 42 a four-sided pocket that receives the head.

This remote control attachment is readily applied to the brush handle by merely removing the 15 nut 33 and telescoping the apertured portion 34 over the exposed threaded end 32 and in this movement registering the remote control device such that the head of the valve 29 nests in the 20 pocket, as shown in Fig. 2. Thereupon the nut 33 is replaced which secures the handle in position and permits valve control by manipulation of the remote control device. This permits the 25 brush operator to operate valve 29 to control the supply of paint to the bristles, such control being effected by the operator independent of the position in which he holds the brush. This device, therefore, prevents fatigue and does not necessitate the brush operator always holding the 30 brush in a predetermined position—that is, a position wherein the thumb always must be in registration with the valve 39. It is to be understood Figs. 1 and 2 relate to the same brush, although the latter figure shows the addition of the 35 remote control attachment.

Reference will again be had to Fig. 1. In this figure the handle structure adjacent the valve 29 is shown provided with a shoulder 43 and between said shoulder and the embossment 44 on the head 40 is interposed a gasket 45.

Slidably mounted in each of the tubes 17 is a flexible tube 46. This tube, as shown clearly in the lower left hand portion of Fig. 1, is a double wound spring, the exterior tubular spring structure being indicated by the numeral 46a and the interior by the numeral 46b. The upper end of the tubular portion supports an externally threaded tubular head 47 having a diametrical slot 48 therein for screw driver engagement. If desired, 45 the connection between the tube 46 and the tubular head may be of rotative character. In normal operation, however, the two are rigidly associated together. In either event, the rotation of the tubular head secures axial adjustment of the tube 50 46. The limit of such adjustment is shown by the dotted lines in the left hand portion of Fig. 1 about the middle of the figure.

The lower end of the tube 46 is provided with a metallic tip having the tubular portion 49 and 60 the flattened flared portion 50. The same supports and discharges into an elongated flexible tip structure having the tubular portion 51 and the flattened portion 52. A split ring or lock 53 secures the metallic tip to the end of the tube 46 65 and when thus secured, it will be obvious that the flexible tips are simultaneously secured to the tubes.

Whenever it is desired to yieldingly associate the flexible tubes together for substantial unit 70 movement and prevent undue relative movement therebetween, the purpose for which will be readily apparent to painters, there is provided a flexible connection. This may be merely a leather strip 54 apertured at 55 and the tubes 46 are positioned in the apertures. Thus, all the tubes 46

are connected together for relative unitary movement, although relative independent movement within the limits of the tying or connecting device is permitted.

Each of the apertures 11 is provided with a 5 tube 17 and each tube 17 supports a tubular structure such as last described, provided with the flexible leather tip 52. The central tubular supply means is mounted slightly differently and reference will now be had to substantially the 10 central portion of Fig. 1.

Tubular member 15 has its coaxial opening 16 internally threaded in the same manner as the interior of the tubes 17 are threaded as at 18. It also is externally threaded near its upper end 15 as at 56 and is threaded into a nut 57 embedded or molded in the chamber exposed face of the base 10. A nut 58 is threaded upon the opposite end 59 of the enlarged portion 15 and bears against the bristle supporting face of the base. 20 Thus, member 15 is rigidly locked in and to and supported by the base 10. The tubular extension 59 terminates at its lower end in a frusto-conical portion 60, portions 59 and 60 being substantially similar to the bristle exposed portion of tube 17 25 and its frusto-conical end 19. The interior of extension 59 is threaded as at 61 similar to the threading 18 in tube 17, so that one of the flexible tube units 46 with its tubular threaded member 48 may be associated therewith and with member 15.

Somewhat similar to the anchorage between the handle and the base shown in the before mentioned application, there is herein illustrated an anchorage as follows: Portion 15 includes an 35 opposite tubular extension 62 which may or may not be internally threaded, as desired. It is, however, externally threaded as at 63 to receive the internally threaded portion 27 of the tubular portion 26. Member 15 by reason of its threaded 40 engagements with the respective nuts 57 and 58 is non-rotatably mounted in the brush base 10 and when the tubular portion 26 of the handle structure is inserted in the aperture in the head 20 and threaded engages the threaded extension 45 62 of the member 15, the handle and the base are drawn together with the gaskets 45 and 23 interposed therebetween and with the head structure 20 between the gaskets. Thus, a closed 50 and relatively sealed supply chamber is provided, paint being supplied through the tubular handle and discharging to the tube 17 by way of the chamber 21 fed by ports 28, the central tubular structure being fed direct from the handle.

From the foregoing it will be obvious that, 55 as the several threaded members 47 are gradually elevated toward the base 10 to retract the discharge ends of the tubes in accordance with bristle wear or for flow adjustment and smoothness of operation, the life of the brush is determinable by the wear to which the bristles are subjected and the final limit of tube adjustment.

For cleaning purposes, the chamber may be readily opened by disconnecting the handle from the base which exposes the interior of the handle 65 for cleaning purposes, the head exposed portion of the base for cleaning purposes and the head passage and chamber. The metallic tip and the flexible tip may be readily detached from the free end of each flexible supply tube, and then if the 70 connecting member 54 is employed, it may be removed from all of the tubes. Thereupon each of the members 47 together with the tubes 46 may be unthreaded from the tube 17 and these tubes 46 cleaned. Then the tubes 17 and 59 as 75

well as the bristles may be cleaned. In this way the entire brush may be made ready for subsequent use with a different color or paint material.

5 By the terminology "paint" herein, the same is used broadly and refers to any liquid surface covering material that may be applied like paint, even though not specifically of paint character, such as for example, enamel, and the like.

10 In Fig. 3 there is illustrated a modified form of the invention and for clearness only a portion of the handle is illustrated and the remote control attachment intentionally has been omitted. In this disclosure, there is illustrated a base 110 to which is suitably secured bristles 114 and the band 124 is suitably associated therewith. A head member 120 includes a chamber 121. The head member bears on a gasket 123 and bearing on the head member is a gasket 145. The handle 131 having the valve structure 129 includes the compression shoulder 143.

15 The brush shown herein is not a wide flat brush but a single feed brush, the base 110 being provided with a bore 113 therethrough and having suitably secured thereto the nut 157. The tubular member 115 has threaded connection with the nut 157 and is clampingly associated with the base by the nut 158. The tubular member 115 includes the tubular extension 159 having the frusto-conical end 160 receiving the flexible tube 146, the latter supporting the metallic tip 150 secured as at 153 and supporting the flexible tip 152.

20 The member 115 includes an opposite extension 162 which is externally threaded and is adapted to have threaded connection with the interiorly threaded extension on the handle 131, which extension is substantially identical to that shown at 26 in Fig. 1. It is, of course, to be understood that threaded within the tubular portion 159 is the threaded member 47.

25 While the invention has been illustrated and described in great detail herein, the same is to be considered as illustrative and not restrictive in character. The several modifications herein illustrated and/or described as well as others which will readily suggest themselves to persons skilled in this art, are all considered to be within the broad scope of the invention, reference being had to the appended claims, although the subject matter common to the present invention and the invention disclosed in the before mentioned copending application is specifically disclaimed herein, because it is claimed in the copending application.

30 As shown herein, the handle structure is interchangeable with respect to the brush heads and bases shown in Figs. 1 and 3 as well as others of similar character for other specific types of work.

35 The invention claimed is:—

40 1. In a fountain brush, the combination with a base, bristles supported thereby, and a handle, of a flexible supply tube supported by the base and enclosed by the bristles and terminating short of the free end thereof, a detachable metal tip secured to the bristle end of the tube, said tip being flared outwardly at its free end, and flexible distributing tip means upon the bristle end of the tube and extending beyond the metal tip toward the bristle free ends and secured to the tube in the anchorage of the tip thereto.

45 2. In a fountain brush, the combination with an apertured base, bristles supported thereby, and a handle, of an interiorly threaded tube in the base aperture, extending toward the bristle

5 tips and enclosed by the bristles and having a restricted outlet, a flexible supply tube supported in the threaded tube and having a threaded portion threaded therein for relative adjustment therebetween for the purpose described, and a flared tip means detachably secured to the free end of the supply tube, said threads permitting removal of the flexible tube from the base.

6 3. A device as defined by claim 2, characterized by the flared tip means including a metallic tip member and a flexible tip, the latter projecting beyond the former but terminating short of the bristle tips, said flexible tip being secured to the flexible tube by the metallic tip member.

7 4. In a fountain brush, the combination with an apertured base, bristles supported thereby and a handle, of an interiorly threaded tube in the base aperture, extending from the base toward the bristle tips and enclosed by the bristles and terminating approximately midway of the length of the bristles, and a supply distributing tube therein having threaded engagement with the interior threading and projecting from the threaded tube toward the bristle end, the threaded connection permitting positioning of the bristle end 25 of the distributing tube in predetermined relation to the bristle ends in accordance with bristle wear.

8 5. In a fountain brush, the combination with a bristle supporting base having supply means carried by the base and enclosed by the bristles, and a relatively independent, detachable and apertured head, of an anchoring handle structure having one end arranged for connection to the base for clampingly associating the base, head 35 and handle together and the other end arranged for supply connection, comprising a valve, a tube, a coupling therebetween, a nut on the other end of the tube, and a tubular handle member supported by and enclosing the tube and retained thereon by the coupling and nut.

9 6. A device as defined by claim 5, characterized by the addition of a remote control attachment having one end juxtaposed relative to the bristles, an intermediate portion interlockingly 45 associated with the valve, and an apertured and laterally projecting opposite end seated on the said other end of the tube between the handle member and the nut.

10 7. In a fountain brush, the combination with a handle, a brush base and bristles secured thereto, of metallic flexible tube means supported by the base and enclosed by the bristles and terminating short of the free ends thereof and valve means controlling the supply to the tube means, 55 said tube means including a pair of spirally wound wires, one within the other and in contact with each other.

11 8. In a fountain brush, the combination with a handle, a brush base and bristles secured thereto, 60 of metallic flexible tube means supported by the base and enclosed by the bristles and terminating short of the free ends thereof and valve means controlling the supply to the tube means, said tube means including a pair of spirally wound 65 wires, one within the other and in contact with each other, a flared and flattened tip on the free end of said tube means.

12 9. In a fountain brush, the combination with a handle, a brush base and bristles secured thereto, 70 of metallic flexible tube means supported by the base and enclosed by the bristles and terminating short of the free ends thereof and valve means controlling the supply to the tube means, said tube means including a pair of spirally wound 75

wires, one within the other and in contact with each other, a flared and flattened metal tip on the free end of said tube means, and a flared and flattened flexible tip projecting therefrom and into which the metal tip discharges, said metal tip being enveloped by the flexible tip.

10. In a valve controlled fountain brush, the combination of a tubular handle, valve means at one end thereof having a brush exposed portion for manual operation, supply means at the opposite end of the handle and detachably connected thereto, a brush body connected to the valve

end of the handle, and an elongated remote control device anchored at one end to the handle at the supply connection thereof and coextensive with the handle and projecting beyond the same in lapping relation to the brush body, said device including a complementary intermediate portion for detachable association with the valve exposed portion whereby device operation at any portion throughout the elongated length secures valve operation.
